BEAM HANGER

William J. Gourley and Fred H. Barney,
Fort Worth, Tex.

Application November 23, 1933, Serial No. 699,420

9 Claims. (Cl. 74—103)

This invention relates to new and useful improvements in beam hangers.

One object of the invention is to provide an improved beam hanger for pump jacks, walking beams and the like, which will act to impart a straight-line stroke to the reciprocations of the polish rod, and do so in a more effectual and satisfactory manner.

A particular object of the invention is to provide a beam hanger wherein abutments and other stops are eliminated from the underside of the beam and whereby a positive stop is carried by the beam above the suspending pivot of the top link or stem.

An important object of the invention is to provide a hanger having pivoted links, the upper suspending link carrying a stop element co-acting with the lower link so that when the upper link is stopped or arrested during the upper portion of the swing, the lower link will be held so as to impart a straight-line movement to the vertical reciprocation of the polish rod. The advantage of such an arrangement is that the lower swinging link, which carries the polish rod, does not strike an abutment on the beam, but is merely guided by the stop element, which in turn is arrested by the top stop. This tends to eliminate whip from the polish rod, as well as to reduce the shock incident to the stop engagement.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a walking beam equipped with a hanger constructed in accordance with the invention,

Figure 2 is a detail of the hanger with the beam at its horizontal position or mid-portion of its swing,

Figures 3 and 4 are similar views showing the beam at the lower and upper ends, respectively of its swing,

Figure 5 is an enlarged front elevation of the hanger and beam,

Figure 6 is a plan view of the same,

Figure 7 is a vertical sectional view taken on the line 7—7 of Figure 5,

Figure 8 is a horizontal cross-sectional view taken on the line 8—8 of Figure 5,

Figure 9 is a side elevation of a modified form

of hanger constructed in accordance with the invention and in its mid position,

Figure 10 is a front elevation of the same,

Figure 11 is a plan view of the hanger,

Figure 12 is a view similar to Figure 9 showing the hanger and beam at the upper end of the swing,

Figure 13 is a vertical sectional view of the hanger shown in Figure 9, and

Figure 14 is a side elevation showing still another form.

In the drawings the numeral 10 designates a walking beam which may be mounted on the usual prop 11, as is shown in Figure 1, or which may be fulcrumed in a pump jack (not shown). The invention being in the hanger, it may be used wherever found desirable. The beam is preferably formed of two channels with their flat sides 12 facing each other and spaced apart, and their flanges 13 directed outwardly. However, any beam construction suitable for the purpose may be used.

The hanger primarily comprises an upper link 14 and a lower link 15. These links may be made of any heavy material suitable for the purpose. The upper link 14 includes a transverse pivot pin 16, a channel shaped hanger bar 17 and a lower transverse pivot pin 18 carried by the bar and on which the upper ends of the side bars 15' of the lower link are pivoted. The side bars carry a rod clamp 19 at their lower ends having trunnions 20 journaled in the caps 21 formed integral with the lower ends of said side bars. The clamp 19 supports the polish rod 22. The side bars 15' carry caps 21' at their upper ends for housing the ends of the pin 18.

For suspending the links, bearing boxes 23 are fastened on the top flanges 13 of the beam 10 and the ends of the pivot pin 16 are housed therein. The hanger bar 17 is fastened on the pins 16 and 18 and extends between the channels of the beam. A transverse stop bar 24 is fastened to lugs 25 on the front edges of the side bars 15' of the lower link 15 in the path of the lower end of the hanger bar. When the beam is swung from its lowest position (Figure 3) to its mid-position (Figures 2 and 7), the lower end of the hanger bar will engage the rear side of the stop bar 24.

For holding the hanger bar in position during the upper portion of the swing, a pair of finger or stop bars 26 fastened to the sides of the beam incline upwardly and are bent inwardly so as to lie contiguous to the sides of the hanger bar 17. Inwardly bent fingers or hooks in the upper ends of these bars engage over the front edges of the

hanger bar and provide positive stops, whereby the said hanger bar is held in an inclined and rigid position during the upper swing of the beam. By holding the hanger bar in position it in turn holds the lower link in position to guide the polish rod in a vertical line. When the beam is swung upwardly to its mid position, the hanger bar 17 will engage its stop bars 24 and 26 at substantially the same time, thus eliminating the shock which occurs when a link swings into engagement with the beam or an abutment thereon.

Where it is not desired to use the inclined stop bars 26, the bearing boxes 23 may be provided with hooks 27 (Figures 9 to 13) for engaging the front edges of the hanger bar 17. A transverse stop bar 24' secured to the rear edges of the side bars 15', takes the place of the bar 24. In Figure 14 a wing 28 is formed on the rear side of the hanger bar 17 and the upper rear end of this wing engages a stop bar 29 fastened on the beam channels. This wing swings between the channels, but otherwise the hanger is the same as first described. The wing is a part of the link 14.

The description which has been given recites more or less detail of a particular embodiment of the invention, which is set forth as new and useful; however, I desire it understood that the invention is not limited to such exact details of construction, because it is manifest that changes and modifications may be made within the scope of the appended claims without departing from the spirit of the invention.

What we claim and desire to secure by Letters Patent, is:

1. A beam hanger comprising, a swinging beam, a pair of links pivoted together, rigid stop means carried by the beam and unattached to said links for engaging one of the links, stop means carried by one of the links for engaging the other link to arrest said links, and a rod clamp carried by one of the links.

2. A beam hanger comprising, a swinging beam, a pair of links pivoted together, rigid stop means carried by the beam and unattached to said links for engaging one of the links, stop means carried by the other link for engaging the first link and co-acting with the first stop to arrest said links, and a rod clamp carried by one of the links.

3. A beam hanger comprising, a pair of upright links pivoted together, one of said links being a hanger bar supporting the other link, said bar being mounted on the pivots of both links, stops engaging both the ends of the hanger bar

for arresting the links, and a rod clamp carried by one of the links.

4. A beam hanger comprising, a pair of upright links pivoted together, one of said links being a hanger bar supporting the other link, said bar being mounted on the pivots of both links, a stop for engaging the upper end of the hanger bar to hold it in position, a stop on the lower link for engaging the lower end of said bar, and a rod clamp carried by the lower link.

5. A beam hanger comprising, a pair of upright links pivoted together, means for pivotally suspending the upper link from a swinging beam, a stop for engaging the upper link above its pivot, a stop for engaging the upper link below the pivot of the lower link, and a rod clamp carried by the lower link.

6. A beam hanger comprising, a pair of upright links one of which includes a hanger bar, means for suspending the hanger bar from a swinging beam, a stop carried by the beam for engaging the upper end of the bar, a stop carried by the lower link for engaging the lower end of said bar to arrest said links, and a rod clamp carried by the lower link.

7. A beam hanger comprising, a swinging beam, bearing boxes mounted on said beam, a pin journaled in said boxes, a hanger bar mounted on said pin, a link suspended from said hanger bar, a pair of stop bars mounted on the beam and engaged by the upper end of the hanger bar, a transverse stop bar carried by the link and engaging the lower end of the hanger bar, and a rod clamp carried by the link.

8. A beam hanger comprising, a swinging beam, bearing boxes mounted on said beam, a pin journaled in said boxes, a hanger bar mounted on said pin, a link suspended from said hanger bar, a pair of stops carried by the bearing boxes and engaged by the upper end of the hanger bar, a transverse stop bar carried by the link and engaging the lower end of the hanger bar, and a rod clamp carried by the link.

9. A beam hanger comprising, a swing beam, a plurality of links suspended from the beam, a polish rod clamp carried by one of the said links, means located adjacent the suspending pivot for engaging the upper link for stopping the same in a predetermined position, and stop means for engaging another of the links and co-acting with the first stop means.
